UNITED STATES PATENT OFFICE.

GEORGE DUNCANSON, JR., OF JERSEY CITY, NEW JERSEY.

PRINTER'S QUOIN.

1,375,495.

Specification of Letters Patent. Patented Apr. 19, 1921.

Application filed April 27, 1920. Serial No. 377,056.

To all whom it may concern:

Be it known that I, GEORGE DUNCANSON, Jr., a citizen of the United States, and a resident of Jersey City, in the county of 5 Hudson and State of New Jersey, have invented a new and Improved Printer's Quoin, of which the following is a full, clear, and exact description.

The present invention relates to new and 10 useful improvements in printers' furniture, and it pertains more particularly to devices of this character known as printers' quoins.

It is one of the primary objects of the present invention to so construct a printer's 15 quoin that the two members constituting the quoin will be positively guided in their movements relatively to each other during the operation thereof.

It is a further object of the invention to 20 provide means for maintaining the two members against relative movement when they have been set in operative position.

It is a still further object of the invention to obtain the heretofore mentioned advantages 25 in printers' quoins without altering the construction of the engaging surfaces of the two members serving to make up a quoin, thus rendering them capable of use with chases or frames of ordinary construction.

30 With the above and other objects in view, reference is had to the accompanying drawings, in which—

Figure 1 is a plan view partly broken away of a device constructed in accordance 35 with the present invention;

Fig. 2 is a side elevation, partly in section, of the device in its closed position;

Fig. 3 is a similar view of the device in its open position, and

40 Fig. 4 is a vertical sectional view taken on the line 4—4 of Fig. 3.

Referring more particularly to the drawings, the device comprises two blocks 5 and 6, and each of these blocks 5 and 6 is provided with an angularly disposed face 7 and a straight face 8.

Secured to the block 6 on its angularly disposed face 7, by means of a pin 9', is a stationary guide 9, one end of which is 50 notched as at 10, to receive the stationary guide 9 to maintain the blocks in proper relation to each other. The block 6 is provided on one end with a cut-out portion 11, and extending transversely of the cut-out portion 11 and spaced from the lower wall 12 thereof, is a pin 13. This pin also serves

to retain the blocks 5 and 6 together in such a manner as to provide a single unit quoin.

The block 5 is provided with a bar 14, which is spaced from its angularly disposed 60 face 7 by means of a spacing block or the like 15, and said bar 14 is secured to the block 5 by means of threaded bolts or pins 14'. This spacing block 15 is so positioned with respect to the block 5 as to maintain 65 the bar 14 in parallelism with the angular wall or face 7 of said block, it being understood that the opposite end 16 of said block is notched as at 17, to receive the bar 14. This bar 14 is provided throughout the 70 major portion of its length with a plurality of spaced notches adapted for engagement with the pin 13 to prevent relative movement of the blocks 5 and 6 under ordinary 75 operating conditions.

To provide for the movement of the blocks 5 and 6 relative to each other in the operation of the quoin, these blocks are provided with notches 20 in their angular faces, and said notches 20 are adapted to be engaged 80 by means of a key or wrench as in the ordinary manner. It has been found, however, that in these devices it is advantageous to provide a reinforcement for blocks, and therefore the notches have been filled in 85 throughout a portion of their length with lead or other suitable reinforcing composition 21. This reinforcing material may also be formed as an integral part of the blocks, if desired. 90

From the foregoing description, it will be apparent that when the quoins are positioned between the chase and the type and are moved with respect to each other to lock the type in the chase or frame, the pin 13 95 will engage one of the notches 18, and the relative position of this pin to the notches 18 will prevent the slipping of the blocks 5 and 6 relatively to each other under ordinary conditions. Such a construction 100 greatly enhances the qualities of devices of this character over the common type in which the frictional contact of the angular surfaces one with the other and the frictional contact of the straight surfaces with 105 the walls of the chase or frame are relied upon to retain the blocks of the quoin against relative movement one to the other.

Having thus described the invention, what is claimed is:

1. A printer's quoin comprising two members having angular faces in sliding contact

with each other, a pair of spaced lugs formed on one of the members, a spaced bar carried by the other of said members and adapted to travel between the spaced lugs to form guiding means, and a transversely-extending pin overlying the spaced bar whereby relative movement of the members is prevented.

2. A printer's quoins comprising two members having angular faces, spaced lugs car-

ried by one of said members, a spaced bar carried by the other of said members and provided with a plurality of notches, and a transversely-extending pin mounted in the lugs and adapted for engagement with the 15 notches in said spaced bar, said pin serving to prevent relative movement of the members in all directions.

GEORGE DUNCANSON, JR.
